UNITED STATES PATENT OFFICE.

CHARLES M. WELCH, OF OGDEN, ARKANSAS.

TRANSFORMER.

Application filed August 26, 1921. Serial No. 495,522.

The object of my invention is to secure a directed settling of water and foreign matter from the body of insulating fluid adjacent an electrical device, and means for isolating the precipitated fluidity substance from the insulating fluid proper.

The invention will hereinafter be more particularly described as embodied in an improved fluid insulated electrical transformer. In this apparatus, water may be introduced into the fluid by a number of causes, chief among which is condensation from the atmosphere under change of temperature. The presence of water in the insulating fluid, is a series menace to the device, since it may be carried by the convecting fluid to points of potential difference, resulting in insulation break down.

The specifications, drawings and claims set forth herein what I believe to be the points of novelty in my present invention, and whereas other arrangements and modifications may be made, I intend to cover all such arrangements and modifications which do not depart from the spirit and scope of my invention.

Referring to the drawings: similar letters refer to similar parts throughout the views in which:

Fig. 1, represents a top view of the casing of a fluid insulated transformer. Fig. 2, represents the transformer in section showing the arrangement of the various parts in relation to the invention.

In Fig. 1, is shown a fluid insulated electrical transformer, with a top cover piece A, an enclosing drum container B, pole hanger hook C, supporting lug D, terminal outlet pipe E, case fitting F, insulating block G, low tension terminal H, lifting ring I, high tension terminal outlet opening J, removable fluid inlet plug K, top annular flange L, drum annular flange M, clamping bolts N, core and coil frame O, core and coil frame supports P, core Q, coils R, core clamps S, fluid outlet plug T, annular drain shelf U, casing bottom V, opening in shelf W, and an annular compartment X.

Electrical devices of the fluid insulated type are commonly filled with oil. When the active elements of the device are at rest, or, are not throwing off sufficient heat to agitate the fluid by convection circulation, any water in the fluid will settle by gravity to a lower level. The insulating fluid may be free from water proper, and yet hold

water vapor in suspension. While there is no affinity between water and oil, I have experimented with the peculiar affinity of vapor and oil. During periods when the device is under load and high temperature, water vapor may rise from the fluid and condense against points of cool surface forming water drops inside the container. These water drops drip into the fluid and gravitate to the bottom of the container.

When water or other heavy matter in the insulating fluid gravitates through the fluid medium, the shelf or baffle U provides a drain through the opening W. The bottom V forms the compartment X between the bottom and the shelf or baffle. The watery fluid like substance contains much dangerous matter in solution and suspension such as sulphur, acid, alkali, carbon, metal dust, and the like, which are as dangerous to electrical insulation as water; and all of which is therefore confined and practically isolated in the space or compartment X from the main body of insulating fluid surrounding the device. This fluidity substance may be drained off or washed out at intervals through the outlet plug T, which plug T closes a vent to the atmosphere.

But while the action of my improvement secures a directed settling of the insulating fluid as hereinbefore described, its primary function is to prevent carrying the settlings of precipitated matter by circulation of the fluid to points of danger to the device. In this latter connection, it is obvious the funnel shaped baffle U interferes with fluid from below rising above the baffle plate into the region surrounding the device. And moreover, the baffle U also prevents the fluid from above from flowing freely by convection into the region below the baffle plate.

I have demonstrated by experiment that transformers in service on distribution lines contain much water and foreign matter in the insulating oil. Settlings occur in the bottom of the cases when the transformers are not loaded, but when the load is on these settlings are washed by the circulating oil into the oil ducts in the coils where the water is absorbed by the insulation and the windings are plastered with material which prevents free radiation of heat and increases the leakage and hazard of breakdown. In this connection, the simplicity and cheapness of my improved construction renders it convenient to install during the manufacture

of sheet metal containing cases. Under service conditions, my improvement reduces the energy losses of the transformer with consequent increase in capacity rating for the device, and it also insures a longer life to the insulation.

I find in the case of small high voltage transformers where insulating fluid of high power is desired, that I am able to keep the oil around the coils in a dry state because the small amount of moisture condensing near the surface of the fluid is precipitated to the bottom where it is isolated from dangerous proximity to the active elements through the medium of my improvement.

As before pointed out, my invention consists in providing a shelf or baffle having an opening adjacent the bottom of the casing forming a compartment having an outlet, whereby the object is accomplished in securing gravity settling of the fluid into the compartment and prevention of the settling circulating back into the fluid surrounding the device; hence I form the baffle so that its portions are adapted to receive and direct the drainage of the settling through the opening into the compartment below and prevent free circulation between the fluid in the compartment and the heated fluid surrounding the device.

The described funnel shaped baffle is the best means known to me at this time for carrying the invention into effect. In my claims annexed to and forming a part of this specification, I do not desire to be restricted in the choice of material construction except as defined by my said claims.

What I claim is:

1. The combination with a fluid insulated electrical device, a casing therefor, a shelf adjacent the bottom of the casing having portions adapted to drain the fluid, a compartment formed by the said shelf and the bottom of the casing, and an opening through the said shelf communicating between the said compartment and the fluid surrounding the said device.

2. The combination with a fluid insulated electrical device, a casing therefor, a shelf adjacent the bottom of the casing having portions adapted to receive and direct the drainage of the settling from the fluid, an

opening through the said shelf draining the said settling, and a compartment formed by the said shelf and the bottom of the casing into which the said settling from the fluid are drained.

3. The combination with a fluid insulated electrical device, a casing therefor, a baffle adjacent the bottom of the casing forming a compartment with the said bottom of the casing, an opening into the said compartment through the said baffle, and portions of the said baffle adapted to prevent free circulation between the heated fluid surrounding the device and the fluid in the said compartment.

4. The combination with a fluid insulated electrical device, a casing therefor, a baffle having an opening adjacent the bottom of the casing, a compartment formed by the said baffle and the bottom of the casing, the said opening communicating between the fluid surrounding the device and the said compartment, the said baffle being formed to receive and direct the drainage of precipitated watery settling from the fluid surrounding the said device through the said opening into the said compartment, portions of the said baffle adapted to prevent free circulation between the heated fluid surrounding the device and the said watery precipitated fluid in the said compartment, and a means in the said compartment for outlet of fluid.

5. The combination with a fluid insulated electrical device, a casing therefor, a funnel shaped baffle plate inside the casing adjacent the lower portion thereof, a hole in the said baffle plate through which the fluid may drain, and a means below the said baffle plate for outlet of fluid from the casing.

6. The combination with a fluid insulated electrical device, a casing therefor, a funnel shaped baffle plate having an opening adjacent the bottom of the container and forming a compartment, whereby the free circulation of the heated fluid adjacent the said electrical device and the fluid within the compartment is prevented, and a means in the said compartment for outlet of fluid.

In testimony I affix my signature at Ogdensburg, Arkansas, August 22, 1921.

CHARLES M. WELCH.
